PSEUDO-AZIMIDO-BENZENE-AMINO-ACYL-OACETIC ACID ESTERS

Hans Johner and Gérald Bonhôte, Basel, Switzerland, assignors to the firm Society of Chemical Industry in Basle, Basel, Switzerland

No Drawing. Application July 12, 1937, Serial No. 153,279. In Switzerland July 14, 1936

8 Claims. (Cl. 260—308)

The present invention relates to new arylides of β -ketone-carboxylic acids which are valuable intermediate products for the manufacture of dyestuffs. It comprises the new arylides, the process of producing the same as well as their application for the manufacture of dyestuffs.

It has been found that valuable arylides of β -ketone-carboxylic acids may be obtained if amino compounds of the general formula

in which R stands for an aryl radical of the benzene or naphthalene series such as the 5-amino-2-phenyl-pseudo-azimidobenzene, the 5-amino-6-methyl-2-phenyl-pseudo-azimidobenzene, the 5-amino-2-(4'-methoxy)-phenyl-pseudo-azimidobenzene, the 5-amino-2-(4'-ethoxy)-phenyl-pseudo-azimidobenzene, the 5-amino-6-methyl-2-(4'-methoxy)-phenyl-pseudo-azimidobenzene, the 5-amino-6-methyl-2-(4'-ethoxy)-phenyl-pseudo-azimidobenzene, the 5-amino-6-methoxy-2-(4'-methoxy)-phenyl-pseudo-azimidobenzene, the 5-amino-6-methoxy-2-(4'-ethoxy)-phenyl-pseudo-azimidobenzene, the 5-amino-2-(4'- β -methoxy-oxyethyl)-phenyl-pseudo-azimidobenzene, are condensed with esters of β -ketone-carboxylic acids, such as ethyl acetoacetate, benzoyl acetic ester, or terephthaloyl acetic ester.

These arylides thus correspond to the general formula

in which R stands for a member of the group consisting of aryl nuclei of the benzene and naphthalene series, R₁ stands for a member of the group consisting of methyl and phenyl, and y stands for a member of the group consisting of H, CH₃ and O-alkyl. Among such products those are valuable in which R represents a nucleus of the benzene series because they lead to particularly valuable dyestuffs. Among such products those are again particularly valuable which correspond to the general formula

in which y has the signification already indicated above and x stands for a member of the group

consisting of H, CH₃ and O-alkyl. All these products are light colored powders insoluble in water but soluble in aqueous caustic alkalies.

The new arylides, which represent valuable intermediate products for the manufacture of dyestuffs, dissolve in aqueous caustic alkalies owing to the presence of the —CO—CH₂—CO— group. In such solutions the alkali salts of the new arylides possess a marked affinity for the vegetable fiber, which is entirely surprising, since the similar arylides from the isomeric amino-azimides do not possess such an affinity for the vegetable fiber. Since they combine with diazo compounds to azo-dyestuffs they are inter alia very suitable for the production of azo-dyestuffs on the vegetable fiber (cotton, ramie, flax, jute and the like) as well as on regenerated cellulose (viscose or cuprammonium silk), and also on animal fibers such as wool, natural silk or loaded silk, according to the methods usual in dyeing with ice colours. Such methods are, for example, padding the fiber in an alkaline solution of the new arylide and developing with a diazo compound, preferably one containing no hydroxy-, carboxy- or sulfo-groups. Such diazo-compounds are, for instance, those derived from aniline, ethers or esters of amino-phenols, for example ortho- or para-anisidine, 4-chloro-2-amino-diphenylether, 4:4'-dichloro-2-aminodiphenylether; those derived from monoacylated products from 2:5-diaminohydro-quinone-diethyl- or -dimethylether and benzoylchloride or phenoxy-acetic-acid-chloride; aminoazo-dyestuffs, for instance, 4-amino-5-methoxyazobenzene, 4-amino-2:5-dimethoxyazobenzene, ortho-amino-azo-toluene; further those derived from chlorotoluidines, for instance 4-chloro-2-methyl-1-aminobenzene, 4-chloro-1-methyl-2-aminobenzene; those from nitranilines such as ortho-nitraniline, 1-amino-2-methyl-4-nitrobenzene, 1-amino-2-nitro-4-chlorobenzene, 1-amino-2-nitro-4-methyl- or -methoxybenzene, or 4-nitro-2-methoxy-1-aminobenzene; those derived from ortho- or meta-chloraniline, 2:5-dichloraniline, α - or β -naphthylamine and the like.

For the purpose of producing fast tints on the fiber preparations or printing colors containing them may also be prepared which contain an alkali salt of the new derivatives and a stabilized diazo-compound in the form of a nitrosamine or of a diazoamino-compound. These preparations may be printed on the fiber and then developed to dyestuffs by suitable treatment, for example by passage through an acid. It is also possible to print mixtures of the free diazotizing components or the corresponding N-nitramines and alkali salts of the new coupling components on the fiber and to convert such mixture into dye-

stuffs by development with nitrous acid, and, if desired, subsequent treatment in alkali.

The condensation products of the general formula

- 10 in which R , R_1 and y have the signification indicated above, coupled in substance with the same non-sulfonated compounds with which they are used for the production of fast tints on the fiber, yield pigments which are useful as such,
15 or in coloring lacquers, varnishes or the like.

With sulfonated diazo-compounds wool dyestuffs are in particular obtained. Especially valuable are the dyestuffs which are derived from ortho-hydroxylated or ortho-carboxylated diazo-

20

	β -ketone-carboxylic-acid-ester	Azimide	Melting point from—
25	Ethyl acetoacetate	+5-amino-2-(4'-methoxy)-phenyl-pseudo-azimidobenzene	Alcohol 163° C.
	Do	+5-amino-2-(4'-ethoxy)-phenyl-pseudo-azimidobenzene	Alcohol 19° C.
	Do	+5-amino-6-methyl-2-phenyl-pseudo-azimidobenzene	Alcohol 205° C.
	Do	+5-amino-6-methyl-2-(4'-methoxy)-phenyl-pseudo-azimidobenzene	Chlorobenzene 222° C.
	Do	+5-amino-6-methoxy-2-(4'-methoxy)-phenyl-pseudo-azimidobenzene	Alcohol 168° C.
	Do	+5-amino-6-methoxy-2-(4'-ethoxy)-phenyl-pseudo-azimidobenzene	Alcohol 155° C.
	Do	+5-amino-6-chloro-2-phenyl-pseudo-azimidobenzene	Alcohol 185° C.
	Do	+5-amino-6-methyl-2-(1')-naphthyl-pseudo-azimidobenzene	Chlorobenzene 209° C.
	Benzoyl acetic ester	+5-amino-2-phenyl-pseudo-azimidobenzene	Alcohol 180° C.
	Terephthaloyl-diactic ester	do	Alcohol 280° C.

35 compounds as these products may be converted in substance or on the fiber into metalliferous dyestuffs.

The dyestuffs which may be prepared according to the present process with aid of the new arylides correspond therefore to the general formula

- 45 in which R , R_1 and y have the signification indicated above, and R_2 stands for an aromatic radical selected from the group consisting of aromatic nuclei of the benzene and naphthalene series. If these dyestuffs do not contain sulfo-
50 groups they represent yellow to orange or brown-orange pigments which are insoluble in water. Particularly valuable are the dyestuffs of the formula

- 60 in which R_2 stands for an aromatic radical of the benzene series, if the benzene radical R_2 contains a nitro-group in ortho-position to the $-N=N-$ group. These dyestuffs when produced on the fiber dye the same yellow tints of very good fastness properties, particularly excellent fastness to light.

The following examples illustrate the invention, the parts being by weight:—

Example 1

- 70 21 parts of 5-amino-2-phenyl-pseudo-azimido-benzene are introduced into 200 parts of chlorobenzene, a few drops of diethylaniline are added and the whole is heated to boiling under reflux.

75 The chlorobenzene is then distilled and there

are added gradually 15 parts of ethylacetoacetate. Condensation is continued for 2 hours, during which time the alcohol formed and some chlorobenzene are distilled. When condensation is complete, the mass is cooled, the chlorobenzene is distilled in steam and the condensation product left behind is filtered; it is dissolved in dilute caustic alkali lye and, after filtration from some impurities, the solution is treated with dilute hydrochloric acid to reprecipitate the condensation product.

It is a white powder freely soluble in dilute alkalis and melting after recrystallization from alcohol at 152° C.

The process is similar with the other pseudo-azimides and β -ketone-carboxylic acid esters cited in the introductory paragraphs. The following table shows the melting point of some of such condensation products. —

Example 2

13.8 parts of ortho-nitraniline are diazotized as usual and the product is introduced into a solution of 29.4 parts of the condensation product from 5-amino-2-phenyl-pseudo-azimidobenzene and ethylacetooacetate, 100 parts of sodium hydroxide solution of 36° Bé., 15 parts sodium acetate and 2000 parts of water. The yellow dyestuff formed is precipitated immediately; it is filtered and dried.

If a sulfonic acid, for instance sulfanilic acid, is substituted for the ortho-nitraniline, there is obtained a dyestuff soluble in water.

Example 3

Cotton yarn is impregnated with a grounding prepared by dissolving 3 parts of the condensation product from 5-aminophenyl-pseudo-azimidobenzene and ethylacetooacetate in 300 parts of hot water with the addition of 6 parts sodium hydroxide solution of 30 per cent. strength, 10 parts of Turkey red oil, 15 parts of sodium chloride, and water to make up 1000 parts. The goods are then wrung out and developed in a diazo-solution which has been neutralized with sodium acetate and acidified with acetic acid, and corresponds with 2 parts of 1-amino-2-methyl-4-nitrobenzene per 1000 parts. There is produced a pure greenish-yellow of very good properties of fastness.

Similar tints are obtained with other diazo-components, for instance 1-amino-2-methyl-4-chlorobenzene, 1-amino-2-nitro-4-chlorobenzene, 1-amino-2-nitro-4-methylbenzene. Redder tints are obtained for instance with 1-amino-2-nitro-4-methoxybenzene or ortho-aminoazotoluene.

The goods may also be ground at a raised temperature, for instance at 80° C.; such arylides may also be used for printing.

The following table comprises a number of 75

other dyeing colors which may be made by this invention:— for the vegetable fiber, and react with diazo compounds with formation of azo-dyestuffs.

Diazo-component	Condensation product from ethyl-aceto-acetate with—	Color	5
Ortho-nitraniline	5-amino-2-(4'-methoxy)-phenyl-pseudo-azimidobenzene	Yellow.	
1-amino-2-nitro-4-methyl-benzene	do	Do.	
1-amino-2-nitro-4-methoxybenzene	do	Do.	
Ortho-nitraniline	5-amino-2-(4'-ethoxy)-phenyl-pseudo-azimidobenzene	Greenish-yellow.	
Para-nitraniline	do	Do.	
1-amino-2-nitro-4-methoxybenzene	do	Reddish-yellow.	10
Ortho-aminozo-toluene	5-amino-6-methyl-2-phenyl-pseudo-azimidobenzene	Gold-orange.	
1-amino-2-nitro-4-chlorbenzene	5-amino-6-methyl-2-(4'-methoxy)-phenyl-pseudo-azimidobenzene	Reddish-yellow.	
2:5-dichloraniline	5-amino-6-methoxy-2-(4'-methoxy)-phenyl-pseudo-azimidobenzene.	Yellow.	
4:4'-dichlor-2-aminodiphenylether	do	Greenish-yellow.	
1-amino-2-nitro-4-chlorbenzene	do	Reddish-yellow.	
15 Ortho-nitraniline	do	Yellow.	15

What we claim is:—

1. As new products the arylides of the general formula

in which R stands for a member of the group consisting of nuclei of the benzene and naphthalene series, R₁ stands for a member of the group consisting of methyl and phenyl, and y stands for a member of the group consisting of H, CH₃ and O-alkyl, which products are light colored powders, dissolving in aqueous caustic alkalies, from which solutions they possess affinity for the vegetable fiber, and react with diazo compounds with formation of azo-dyestuffs.

2. As new products the arylides of the general formula

in which R₁ stands for a member of the group consisting of methyl and phenyl, y stands for a member of the group consisting of H, CH₃ and O-alkyl, and x stands for a member of the group consisting of H, CH₃ and O-alkyl, which products are light colored powders, dissolving in aqueous caustic alkalies, from which solutions they possess affinity for the vegetable fiber, and react with diazo compounds with formation of azo-dyestuffs.

3. As new products the arylides of the general formula

in which y stands for a member of the group consisting of H, CH₃ and O-alkyl, and x stands for a member of the group consisting of H, CH₃, O-alkyl and halogen, which products are light colored powders, dissolving in aqueous caustic alkalies, from which solutions they possess affinity

4. As new products the arylides of the general formula

in which y stands for a member of the group consisting of H, CH₃ and O-alkyl, which products are light colored powders, dissolving in aqueous caustic alkalies, from which solutions they possess affinity for the vegetable fiber, and react with diazo compounds with formation of azo-dyestuffs.

5. As new products the arylides of the general formula

in which the alkyl-group contains not more than 2 carbon atoms, and in which y stands for a member of the group consisting of H, CH₃ and O-alkyl, which products are light colored powders, dissolving in aqueous caustic alkalies, from which solutions they possess affinity for the vegetable fiber, and react with diazo compounds with formation of azo-dyestuffs.

6. As a new product the arylide of the formula

7. As a new product the arylide of the formula

8. As a new product the arylide of the formula

HANS JOHNER.
